UNITED STATES PATENT OFFICE

148,218

DESIGN FOR A COMBINED PENCIL AND CIGARETTE LIGHTER

Seymour Fiedler, New York, N. Y.

Application December 18, 1946, Serial No. 135,597

Term of patent 3½ years

(Cl. D74—24)

To all whom it may concern:

Be it known that I, Seymour Fiedler, a citizen of the United States of America and residing in the city of New York, county and State of New York, have invented a new, original, and ornamental Design for a Combined Pencil and Cigarette Lighter, of which the following is a specification, reference being made to the accompanying drawing, forming part thereof.

Fig. 1 is a side-elevational view of a combined pencil and cigarette lighter;

Fig. 2 is a front elevational view showing my new design in a closed condition and

Fig. 3 is a side-elevational view of the design in open condition.

I claim:

The ornamental design for a combined pencil and cigarette lighter, substantially as shown.

SEYMOUR FIEDLER.
